[57] CLAIM

The ornamental design for an adjustable fishing rod support, as shown and described.

DESCRIPTION

FIG. 1 is a perspective view showing a first embodiment of the fishing rod support of this invention in one adjusted position, a bracket not forming a part of this invention being shown in phantom,

FIG. 2 is a side view thereof, the other side having the same appearance,

FIG. 3 is a front view,

FIG. 4 is a top plan view,

FIG. 5 is a bottom plan view,

FIG. 6 is a rear elevation thereof;

FIG. 7 is a perspective view of the fishing rod support of this invention in a second adjusted position, a bracket not forming a part of this invention being shown in phantom;

FIG. 8 is a side view thereof, the other side having the same appearance,

FIG. 9 is a front view,

FIG. 10 is a top plan view,

FIG. 11 is a bottom plan view, and

FIG. 12 is a rear elevation thereof.
